Primary Examiner — Angela J Lee*(74) Attorney, Agent, or Firm* — Whyte Hirschboeck Dudek S.C.(57) **CLAIM**

The ornamental design for blood glucose meter with icon, as shown and described.

DESCRIPTION

FIG. 1 is a front view of a blood glucose meter with icon, but showing the icon separately for clarity of illustration; and, FIG. 2 is a front view thereof, but showing the blood glucose meter in broken lines.

The portions shown in dashed lines do not form part of the design.
